R. C. Bruckner.

UNITED STATES PATENT OFFICE.

JUDGE F. BARKER, OF WAXAHACHIE, TEXAS.

SILO.

1,184,914.

Specification of Letters Patent. Patented May 30, 1916.

Application filed April 19, 1915. Serial No. 22,244.

To all whom it may concern:

Be it known that I, JUDGE F. BARKER, a citizen of the United States, residing at Waxahachie, in the county of Ellis and State of Texas, have invented certain new and useful Improvements in Silos, of which the following is a specification.

My invention has relation to an improvement in silos of that type or class wherein horizontally arranged boards or panels are arranged to slide vertically between adjacent uprights, the series of uprights forming the standards or supports for the structure and in such connection it relates more particularly to the construction and arrangement of said uprights, the connection between the uprights and horizontal panels and the construction and arrangement of the door for said silo.

In the carrying out of my invention the uprights in the form of T beams are supported by the floor of the structure to form a polygonal structure, the space between adjacent uprights being filled by superposed, vertically movable rectangular panels or boards, interlocking at their flat ends with a web of the two webbed head of the beams and separated at their inner portion of their contiguous ends by vertically arranged wedge shaped strips resting at the base of the wedge upon the head of a beam and the sides of the wedge being in sliding contact with the flat ends of adjacent panels. There is further provided removable blocks recessed to fit on the projecting free web of the beam and having a downwardly and inwardly curved indentation on their outer faces to form seats to receive and retain the tie rods for the structure.

The nature and scope of my invention will be more fully understood from the following description taken in connection with the accompanying drawings forming part hereof, in which,—

Figure 1, is a front elevational view of so much of a silo as is necessary to illustrate my invention. Fig. 2, is a horizontal sectional view of the same. Fig. 3, is a vertical sectional view taken on the line y, y of Fig. 1, and Fig. 4, is a perspective view of one of the stay blocks removed from the structure.

Referring to the drawings 1 represents the floor of the silo preferably of circular form and having at intervals around its periphery a series of vertical slots or recesses

2. Each recess is adapted to receive the base of a T beam or upright 3 and to lock the same to said floor 1. The T beams 3 are so disposed that their heads point inward or toward the center of the structure and their stems point outwardly. The beams constitute the supporting corners of a polygonal structure, in the case illustrated in the drawings the polygon is of six sides or hexagonal. The side flanges or webs constituting the head of the beam constitute bearings for superposed, horizontally arranged panels or boards 4 of substantially rectangular shape, the flat ends of the panels having the channels 5 which are wider than the width of the webs of the beam. The panels 4 are arranged to span the head webs of adjacent beams 3 and to have a vertical movement thereon and the contiguous channeled ends of adjacent panels 4 are separated some distance from each other. The space between adjacent contiguous ends of the panels 4 at the inner portion of the panels beyond the head of a T beam 3 is filled by a wedge shaped strip 6 forming a continuation for the head of the T beam and also closely fitting the flat contiguous ends of adjacent panels to complete the continuity of the inner wall of the structure. These strips are trapezoidal in cross section, with the base of the trapezoid resting for support upon the head of the T beam and the inclined sides sliding upon the flat channeled ends of adjacent panels to maintain said panels in water and air tight locking engagement with the wedge, and with the T-beam. The wedges also serve to tighten the sides of the structure when the T-beams are forced inward against the wedges. The preferred means of so forcing the T beams 3 inward or centrally consists of one or more encircling tie rods 8 in sections united together by turn buckles 9 of well known construction and arrangement. Where a rod 8 crosses the stem of a T beam 3 there is preferably interposed between the beam and the tie rod 8, a removable block 9a having inner vertical recess 10 to fit on the stem of T-beam 3 and an outer rounded face having a downwardly and inwardly curved indentation or horizontal recess 11 in which the rod 8 is adapted to be received and retained.

At the corners when the door openings are to be provided, the wedge shaped pieces 6 are replaced by studs or vertical members

12 which are shaped as at 13 to perform a portion of the function of wedges 6 and also are shaped to form jambs as at 14. These jamb edges 14 of studs 12 are inwardly beveled to closely fit the complementary beveled edges of the door 15, so that the door may open inward of the structure. The front of the door 15 is provided with the vertical cleats 16 and transverse cleats 17 uniting several panels 4 into one structure. On each cleat 16 is pivoted as at 18 a latch bar 19 adapted to engage a keeper plate 20 on the outside of each stud 12. The top of the door 15 is beveled outwardly and the contiguous edge 21 of an adjacent superposed panel 4 is likewise beveled and the V shaped slot thus formed is filled by the wedge shaped cross strip 22 firmly held to position by a tie rod 8. At the base of the door a beveled sill 23 serves to render the joint between door and base 1 air and water tight. Having thus described the nature and objects of my invention what I claim as new and desire to secure by Letters Patent, is,—

25 1. In a silo, a series of T beams forming the uprights, a series of rectangular panels sliding between adjacent uprights to form the walls of the structure, each panel having recessed flat ends interlocking with the webs of the head of the T beams, combined with wedge shaped strips interposed between the head of the beam and adjacent flat ends of the panels, the sides of the wedge and said flat ends of said panels being in sliding engagement with each other.

30 2. In a silo, a series of T beams forming

the uprights, a series of rectangular panels sliding vertically between adjacent uprights and superposed to form the walls of the structure, each panel having recessed flat ends, interlocking with the webs of the head of the T beams, a series of strips each trapezoidal in cross-section, the base of each strip resting upon the head of a beam and the inclined sides of each strip being in sliding engagement with an adjacent flat end of a panel, combined with tie rods surrounding the stems of the T beams to interlock the panels, strips and T beams together.

3. In a silo, a series of T beams forming 50 the uprights, a series of rectangular panels sliding vertically between adjacent uprights and superposed to form the walls of the structure, each panel having recessed flat ends, interlocking with the webs of the head 55 of the T beams, a series of strips each trapezoidal in cross-section, the base of each strip resting upon the head of a beam and the inclined sides of each strip being in sliding engagement with an adjacent flat end of a 60 panel, combined with removable blocks recessed to fit upon the stems of the T beams and each having a downwardly and inwardly curved indentation on its outer face and tie-rods surrounding the structure and 65 arranged to enter the indented blocks to interlock the blocks, T-beams, panels and strips together.

In testimony whereof I have signed my name to this specification.

JUDGE F. BARKER.
